(57) CLAIM

The ornamental design for a chair, as shown and described.

DESCRIPTION

FIG. 1 is a front perspective view of my new chair;
FIG. 2 is a bottom perspective view of my new chair of FIG. 1 from the rear of the chair;
FIG. 3 is a front elevational view of my new chair;
FIG. 4 is a rear elevational view of my new chair, opposite that of FIG. 3;
FIG. 5 is a side elevational view of my new chair, the opposite side being a mirror image thereof;
FIG. 6 is a top view of my new chair; and,
FIG. 7 is a bottom view of my new chair.
